MULTIPLE TEMPERATURE REFRIGERATING APPARATUS

John J. Shively, New York, N. Y.

Application November 2, 1938, Serial No. 238,310

11 Claims. (Cl. 62—115)

This invention pertains to multiple temperature refrigerating apparatus.

In my Patent No. 1,907,885 are set forth and claimed a method and apparatus for the operation of a plurality of coolers in conjunction with an accumulator, by which the direct control and functioning of the individual coolers are rendered substantially independent of the operation of the primary refrigerating means.

An object of the present invention is to provide an improved apparatus for controlling the refrigerating fluids within the accumulator and coolers.

A further object is to provide improved accumulator and cooler apparatus for carrying out the above method.

A still further object is to provide apparatus of the above type particularly adapted to the maintenance of a plurality of temperature zones.

Another object is to provide apparatus of the above character comprising means to maintain a plurality of independent temperatures in a single unitary structure.

Still a further object is to provide means to operate a plurality of cooling devices at different temperatures by means of a volatile refrigerant therein while maintaining substantially the same vapor pressure in all said devices.

A still further object is to provide improved means of feeding refrigerant liquid to the individual coolers and to control their temperatures.

Another object is to provide apparatus of the above type in which oil accumulation in the individual coolers is eliminated.

Still another object is to provide a multiple temperature cooling structure which is simple, and which may be readily operated in conjunction with any suitable compression, absorption or other refrigerating means.

Other objects and advantages of the invention will appear during the course of the following description in connection with the accompanying drawing, in which:

Figure 1 is a diagrammatic vertical transverse sectional view of a three-temperature structure illustrating the operation of the invention;

Figure 2 is a vertical sectional view of an alternative three-temperature structure;

Figure 3 is an exterior front view of the device shown in Figure 2;

Figure 4 is a detail view of the type of liquid valve and lever shown in Figure 2;

Figure 5 is a fragmental detail view illustrating the use of internal fins or the like to increase the interior condensing surface in the accumulator;

Figure 6 is a diagrammatic view of a form of

two-temperature unit embodying a flooded primary evaporator; and

Figure 7 is a detail view of a means of distributing liquid refrigerant in a secondary evaporator.

Referring to Figure 1, the numeral 10 generally denotes a three-temperature cooling unit having a low temperature cooler or accumulator section 11, a second cooler section 12, and a third cooler section 13. The section 11 may contain a sharp-freezer pocket 14.

Open passages 15 and 16 lead from the upper portions of coolers 12 and 13 respectively into the upper portion of the accumulator or cooler 11. Liquid passages 17 and 18 lead from the bottom of section 11 into the upper parts of sections 12 and 13. The cooler sections 12 and 13 are preferably of inverted V-shape, and the passages 17 and 18 may terminate in short spouts 19 and 20 overlying the arched or sloped inner walls 21 and 22 forming the roofs of cooling compartments 23 and 24. The liquid passages 17 and 18 are controllable by valves 25 and 26 adapted to be operated by any suitable thermostatic means, illustrated herein by those of the well known type comprising elongated casings 27 and 28 containing expandable bellows members (not shown) and having thermostatic "feeler" bulbs 29 and 30 connected thereto by tubes 31 and 32. The bulbs may be disposed in any desired location with relation to their respective coolers. For instance, the bulb 29 is shown attached to the outer surface of cooler 12, while bulb 30 is disposed within the compartment 24.

One or more of the thermostatic bulbs may also be located in the atmosphere of a refrigerator space to be cooled, as in the case of a refrigerator having two food storage spaces divided by a partition 69, as illustrated by dotted and dashed lines, Figure 1.

The accumulator 11 contains a body of volatile refrigerant 33, the liquid level thereof being below the openings of passages 15 and 16. A primary evaporator, illustrated by a coil 34, is disposed in the accumulator 11 and has inlet and outlet pipes 35 and 36 leading through the walls thereof, the joints being permanently sealed to prevent the escape of the refrigerant 33 and the inlet 35 being provided with an expansion valve 37. Liquid and suction lines 38 and 39 connect the expansion valve 37 and outlet pipe 36 with a condensing unit 40 of any suitable type. A thermostatic switch 41, adapted to control the motor 42 of unit 40, has the usual feeler bulb 43 disposed in heat-exchange relation with the accumulator

section 11, for instance in a sealed tube 44 as shown.

The accumulator section 11 and the liquid passages 17 and 18 preferably are provided with exterior insulation 45.

The operation of the device is as follows:

The condensing unit 40, operating in the usual manner, circulates a primary refrigerant through the primary evaporator 34, thereby refrigerating the secondary refrigerant bath 33. The thermostatic control 41 is so adjusted as to maintain the temperature in the accumulator section 11 at the lowest temperature desired in the system; that is, a temperature substantially below those at which the coolers 12 and 13 are intended to operate.

The thermostatic valves 25 and 26 are set to open and close within temperature ranges above that of the accumulator 11, since the coolers 12 and 13 are adapted to provide zones of higher temperature. Normally, therefore, while the valves 25 and 26 are closed, the interiors of coolers 12 and 13 are maintained substantially dry due to the fact that any comparatively warm vapor from evaporation in these lower coolers rises through the open vapor passages 15 and 16, gives up its heat to the low temperature bath 33, and is condensed therein.

When the temperature of bulb 29, controlling the valve 25 of cooler 12, rises to the maximum of its set range, the valve 25 opens and allows cold liquid from the bath 33 to fall through the passage 17 and spout 19 into the interior of cooler 12. This cold liquid encounters and spreads over the inner surfaces of cooler 12, receives heat therefrom and is vaporized at a temperature higher than that in accumulator 11. The comparatively warm vapor thus evolved passes upward through the passage 15 and is re-condensed in the liquid bath 33. The evaporation in cooler 12 refrigerates the latter until its lowered temperature causes the valve 25 to be re-closed by its thermostat and the liquid flow stopped. The interior of cooler 12 again is dried out or "starved" of liquid and refrigeration therein stops until the next rise in temperatures causes the above operation to be repeated.

From the foregoing description it is evident that section 11 acts as an accumulator for heat, all heat from the lower units 12 and 13 being absorbed in the liquid bath 33 together with such other heat as is absorbed from the sharp-freezer compartment 14, and that the accumulated heat of the entire combination is removed from the bath 33 by operation of the primary evaporator 34. As the bath 33 is of substantial volume and therefore possesses considerable heat storage capacity, it is also evident that the operation of the lower coolers 12 and 13 takes place whether the condensing unit 40 is in operation or not, the latter being controlled to maintain the bath 33 always at lower temperature than that of coolers 12 and 13. Since all coolers are in free vapor communication with the upper portion of accumulator section 11, all coolers are normally at substantially the same pressure, the only difference existing at any time in their cycles being the very small rise in vapor pressure in the lower coolers which causes their warmer vapor to move up through the passages 15 and 16.

Thus, the coolers 12 and 13 are operated at different temperatures not by any attempt to maintain them at different evaporating pressures, but rather by thermostatically controlling

the amounts of liquid fed or "spilled" into them. Their individual temperature adjustments therefore are entirely independent of each other, the only requirement being that both must operate at higher temperature than that of the accumulator or minimum temperature section 11.

Similarly, except for their higher ranges, the temperatures of coolers 12 and 13 have no fixed relationship with that of section 11, since, if the temperature of the latter is changed, the thermostatic valves 25 and 26 simply feed greater or smaller amounts of the sub-cooled liquid to their coolers as required.

The interior surfaces of the coolers 12 and 13 may be shaped in any desired manner to distribute the entering sub-cooled liquid in the most advantageous manner, those shown in Figure 1 having arched inner walls 21 and 22 adapted to spread the film of liquid down both sides of the cooler.

Various distributing devices such as the spreader baffle 68 shown in Figure 7 may also be used.

Obviously the coolers may be provided with thick sections or with brine pockets for storage, with exterior or interior fins, etc., according to the particular type of installation for which the device is to be used.

The valves 25 and 26 are required only to hold the smaller liquid head above them, and need not close with absolute tightness, as small leakage would have negligible effect on the operation, simply lengthening the time between major openings of the valves. The valves therefore require little power of their thermostats, which consequently for some purposes may be of comparatively simple and cheap construction.

Figures 2 and 3 illustrate a three temperature unit in which the higher temperature coolers 46 and 47 are arranged vertically below the low temperature or accumulator section 48. The accumulator, section 48, is adapted to contain a body of liquid refrigerant 48a, with a vapor space 38b above the liquid as in the case of Figure 1. The liquid valves 49 and 50 at the lower ends of liquid passages 17a and 17b, respectively, are controlled by bimetallic helices 51 and 52 adapted to revolve rods 53 and 54 carrying small levers 55 and 56 engaging the valves as illustrated in Figure 4. The bimetallic elements 51 and 52 are adjustably mounted at points relatively remote from the inlets for the sub-cooled liquid so that the latter does not directly influence their temperature, and the rods 53 and 54 may be made of Bakelite or of metal having low heat transmitting coefficient such as stainless steel.

The thermostats are thus influenced principally by the heat transmission and radiation of the adjacent cooler walls. Protecting and sealing caps 57 may be provided over the adjustable mountings of the thermostats. As shown, the accumulator or sharp-freezer section 48 and the second temperature cooler 46 are insulated, from each other and from the outside atmosphere by means of a suitable body of insulating material 48c, the second temperature cooler 46 is adapted to provide an intermediate temperature compartment, while the bottom cooler 47, in addition to providing a mild temperature storage compartment, is exposed to the atmosphere of the refrigerator to provide general cooling and may be provided with exterior fins 58 for this purpose. Obviously this arrangement of the middle and bottom coolers may be reversed,

and if desired both coolers 46 and 47 may be exposed to the atmosphere to refrigerate the latter.

It will be seen that the form of device shown in Figures 2 and 3 comprises a simple and entirely self-contained refrigerating unit for multiple temperatures. Any practical number and arrangement of coolers for different temperatures above the minimum or sharp-freezer temperature may be embodied in any of the types of unit shown by proper proportioning of the parts. It will also be understood by those skilled in the art that any suitable method of construction may be used in the parts, such for instance as the well-known method utilizing joined pressed metal members, as shown for illustration in the construction of the primary cooling coil 59 and sharp-freezer pocket 60, Figure 2.

To increase the interior cooling surface exposed to the vapors entering the accumulator, members such as fins 61, Figure 5, may be employed. The members 61, which may either be attached to the primary coil 62 or may simply be loosely disposed within the accumulator 63, are partly submerged in the liquid bath 64. These members, through their large surface above the liquid level, rapidly absorb heat from the vapor entering through the passage 65 and conduct it into the bath 64, by which means condensation of the vapor is accelerated.

While the vapor return pipes 15 and 16, Figure 1, and 15a and 16a, Figure 2, may be either insulated or exposed, the latter arrangement is preferred in most cases, as a certain amount of additional heat absorbed through them from the atmosphere serves to accelerate the upward passage of the vapors.

In the foregoing illustrations the primary evaporators have been shown as employing expansion valves. Figure 6 shows diagrammatically a two temperature unit 66 in which the primary evaporator uses the flooded system controlled by a float 67.

Instead of employing the binary system as hitherto described, the device may be constructed for direct primary action by the high side unit on the liquid bath in the accumulator. However, the binary system is preferred for several reasons, of which the principal are as follows:

The binary arrangement permits the selection of primary fluid especially adapted to efficient heat removal at low temperatures while a secondary fluid may be selected having other characteristics most suitable for its particular service;

The binary system prevents any difficulty arising from accumulation of lubricant in the lower coolers, since the secondary fluid contains none;

The binary system as disclosed prevents undue loading of the high side at any time, due to the limitation of the primary evaporator surface. When the entire system has been stopped for some time, for instance during shipment, all thermostatic valves are open and the lower coolers are substantially full of liquid, their total internal volume being preferably small enough that a substantial amount of liquid also remains in the accumulator. Under these conditions, when the compressor is started, the entire cooler system at first is refrigerated at the same time, since the liquid has free passage through all the thermostatic valves. As the general temperature falls sufficiently to operate each thermostat the latter closes its particular liquid valve, after which the continued lowering of the accumulator temperature causes the remaining liquid to be

evaporated from the corresponding lower cooler. The sharp-freezer or accumulator temperature continues to fall until further lowering is stopped by the thermostatic switch 41, Figure 1, the lower cooler meanwhile being dried out or "starved" as previously described, and the system assumes its normal operation throughout. During the above starting period from general warm conditions, if the compressor suction were to operate directly on the fluid in the entire cooler unit, a heavy load would be imposed which would either require unduly large high side capacity or would require some type of automatic restricting means to prevent overload. The limited absorbing surface of the primary evaporator noted above, prevents this unduly rapid extraction of heat and thereby distributes the initial load over a longer period, allowing the use of a comparatively small and inexpensive high side unit suited to normal operation of the system.

In the preferred forms of the invention illustrated, the low side structure forms a complete multiple temperature unit in which the secondary fluid may be permanently sealed, the unit being adapted to be connected to any suitable refrigerating machine in the same manner as an ordinary single evaporator. The device has been illustrated as operated in connection with a high side of the compression type, but it will be understood that it is also adapted to operate with absorption systems.

From the foregoing description it will be seen that the invention provides a method of refrigerating a plurality of coolers which consists in maintaining all coolers in open vapor communication, maintaining a substantial body of liquid refrigerant in one of the coolers at the lowest temperature required in the system, and admitting liquid from said body to the other coolers in accordance with their individual requirements.

While the invention has been described in preferred form, it is not limited to the exact structures illustrated as various changes and modifications may be made without departing from the scope of the appended claims.

What is claimed is:

1. In a device of the character described, in combination, an accumulator casing adapted to contain a substantial body of volatile liquid, means including a primary evaporator in said casing in heat exchange relationship with said liquid and adapted to refrigerate said liquid within a pre-determined temperature range, a freezing compartment in said casing, a plurality of secondary evaporators disposed at lower level than said casing, a body of insulating material between said casing and said secondary evaporators, means forming individual passages entirely within said body of insulation and adapted to admit quantities of said liquid from said body to said secondary evaporators, individual thermostatic means operable in accordance with the individual temperatures of said secondary evaporators to control said admissions, the upper limit of said pre-determined temperature range being below any of said individual temperatures, and individual vapor conduits exterior to said insulation and in open communication from said secondary evaporators to said casing.

2. The combination claimed in claim 1 including means to adjust said refrigerating means to vary said pre-determined range and wherein said individual thermostatic control means are adjustable independently of each other and of said refrigerating means.

3. In a device of the character described, in combination, a unitary structure including an accumulator casing adapted to contain a body of volatile fluid, an evaporator below said casing, a body of insulating medium between said casing and said evaporator, a vapor conduit exterior to said body of insulating medium and forming an open communication from the upper part of said evaporator into the upper part of said accumulator casing and a liquid conduit entirely within said body of insulating medium and leading from the lower part of said casing into said evaporator; a valve adapted to control the flow of said liquid through liquid conduit, thermostatic means to control said valve in accordance with the temperature of said evaporator, and refrigerating means to maintain said body of fluid in said accumulator at a temperature lower than the temperature of said evaporator, said accumulator casing including means to conduct heat from an exterior substance directly to said body and said refrigerating means.

4. The combination claimed in claim 3 wherein said volatile fluid is confined entirely within said casing, evaporator and conduits, and wherein said refrigerating means includes a primary evaporator in heat exchange relationship with said fluid in said casing, said primary evaporator having a plurality of heat absorbing fins extending above the level of said body of fluid in said accumulator.

5. The combination claimed in claim 3 wherein said refrigerating means includes means to adjust the temperature maintained in said accumulator, wherein said valve is disposed at the delivery end of said conduit within said evaporator, and wherein said thermostatic valve control means is adjustable independently of said accumulator temperature.

6. The combination claimed in claim 3 wherein said thermostatic means is comprised in said evaporator in heat exchange relation with a wall thereof.

7. In a device of the character described, in combination, an accumulator comprising a chamber adapted to contain a substantial body of volatile refrigerant, means forming an insulating body engaging substantially the entire lower exterior surface of said accumulator, an evaporator comprising a second chamber below said first chamber and having an upper exterior wall engaging said insulating body, an interior wall of said second chamber comprising an upwardly arched middle portion and substantially vertical side portions, an open vapor conduit outside said insulating body and connecting the upper portions of said first and second chambers, a liquid refrigerant conduit leading through said insulating body from the bottom of said first chamber into the top of said second chamber di-

rectly above said arched wall portion, a valve adapted to control the flow of liquid through said conduit, thermostatic means to control said valve, means to refrigerate said body of refrigerant in said accumulator, and means forming a freezing chamber within said accumulator.

8. A unitary cooling device comprising in combination, an upper tank adapted to hold a substantial body of liquid refrigerant and having a vapor space above said liquid, a second tank directly below said first tank and comprising a single chamber of inverted U-shape, an insulating body between said tanks and engaging the same, a vapor conduit outside said insulating body and leading from the upper portion of said chamber to said vapor space in said first tank, a liquid conduit from the bottom of said first tank into the top of said inverted U-shaped chamber, a valve adapted to control liquid flow through said conduit, thermostatic means to control said valve, and an evaporator in said first tank.

9. A unitary cooling device comprising in combination, an upper cooler adapted to hold a substantial body of volatile liquid refrigerant and having a vapor space above said body, a lower cooler under said upper cooler, an open vapor conduit connecting the upper portion of said lower cooler with said vapor space, a liquid conduit connecting the lower portion of said first cooler with the top of said second cooler, a refrigerating evaporator in said first cooler, and a plurality of heat conducting members of substantial surface disposed in said first cooler and extending from below the surface of said liquid body into said vapor space.

10. In a unitary cooling structure, in combination, an accumulator adapted to contain a substantial body of liquid refrigerant, said accumulator having a vapor space above said body of refrigerant an evaporator below said accumulator, a second evaporator below said first evaporator, separate vapor conduits leading from said evaporators to said vapor space, means forming a body of insulation between said accumulator and evaporators and between the atmosphere and said accumulator and said first evaporator, liquid conduits within said insulating body and leading from the bottom of said accumulator into the upper portions of said evaporators, valves in said evaporators at the ends of said liquid conduits, thermostatic means comprised entirely within said evaporators and adapted to control said valves, and means to refrigerate said liquid in said accumulator.

11. A structure as claimed in claim 10 wherein said first and second evaporators are of inverted U-shape and including heat-absorbing fins on said second evaporator.

JOHN J. SHIVELY.
